UNITED STATES PATENT OFFICE.

MAYO SANDS KEATOR, OF CHENEYVILLE, LOUISIANA.

SPOOL-HOLDER.

SPECIFICATION forming part of Letters Patent No. 362,972, dated May 17, 1887.

Application filed January 4, 1887. Serial No. 223,411. (Model.)

To all whom it may concern:

Be it known that I, MAYO SANDS KEATOR, a citizen of the United States, residing at Cheneyville, in the parish of Rapides and State 5 of Louisiana, have invented a new and useful Spool-Holder, of which the following is a specification.

My invention relates to certain new and useful improvements in spool-holders; and it consists of a center plate having a parallel and right-angled finger.

The object of my invention is to hold a spool for any purpose that may be desired by the operator. I attain this object by the mechanism illustrated in the accompanying drawings, in which—

Figure 1 is a view of the blank; Fig. 2, a side view of the spool with the holder applied, and Fig. 3 a view of the finger for holding the spool seated therein and bent to the required form. Fig. 4 shows a modification of the blank.

Similar letters refer to like parts throughout the drawings.

Referring to the drawings, the center plate, A, is made of any desirable shape, preferably heart, and of any suitable material, preferably metal. Projecting from the center plate, A, are fingers E and F, which are a part thereof, one 30 at the narrow end and the other at the broad end of the heart. E, the finger at the narrow end of the center plate, is bent parallel to the center plate, with the exception of being slightly bowed at x, Fig. 2, to give it elasticity. The remainder of the finger is slightly dished 35 to give it rigidity. F, the finger at the broad end of the center plate, is bent at right angles to the center plate, and is made of sufficient length to accommodate the spool. Where it 40 joins the center plate there are cuts D D, made on each side, and another cut, B, extends half the length of the finger. This divides half

the finger into two smaller ones, *i. i.* These have their ends rounded. From where the finger F joins the center plate up to s, Fig. 1, 45 it is turned or made cylindrical. The smaller fingers, *i. i.*, are left flat to act as springs. Said springs have shoulders H, bent outward (see Fig. 3) to prevent the spool from slipping off. The ends of said shoulders are turned up to 50 make convenient the adjustment or removal of the spool by pressing the springs together and then pushing the spool on or off.

The arrangement of this spool-holder may be modified (see Fig. 4) by employing two or 55 more fingers, F, for holding two or more spools. This would necessitate the widening of the center plate, A, and arranging the fingers on each side.

Having thus described my invention, what I 60 claim, and desire to secure by Letters Patent of the United States, is—

1. As an article of manufacture, a spool-holder made from a blank of sheet metal, consisting of a center plate, A, having an attaching-finger, E, formed as described, and a right-angled finger, F, provided with smaller fingers or springs, *i. i.*, having shoulders H, with turned-up ends, substantially as set forth. 65

2. As an article of manufacture, a spool-holder made from a blank of sheet metal, consisting of a center plate, A, having an attaching-finger, E, formed as described, and two right-angled fingers, F, arranged on the side of the center plate, provided with smaller fingers or 70 springs, *i. i.*, having shoulders H, with turned-up ends, substantially as described. 75

In testimony whereof I affix my signature in presence of two witnesses.

MAYO SANDS KEATOR.
